United States Patent Office.

A. M. OLDS, OF NEW YORK, N. Y.

Letters Patent No. 65,588, dated June 11, 1867; antedated May 27, 1867.

IMPROVED SELF-ADJUSTING WRENCH.

The Schedule referred to in these Letters Patent and making part of the same.

Be it known that I, A. M. OLDS, of the city, county, and State of New York, have invented a new and useful "Improved Self-Adjusting Wrench;" and I do hereby declare the following to be a full, clear, and exact description of the construction and operation of the same, reference being had to the annexed drawings, making a part of this specification.

Figure I is a side view, showing the wrench with the movable, self-adjusting arm *b* closed.

Figure II is a back view, showing the shape of the arm *b* and the way in which it is mortised into the handle.

Figure III is a side view, with the movable arm *b* extended to the utmost.

In these figures, *a* is the handle; *b*, the movable self-adjusting arm, constructed so that its inside surface shall form two full sides and one fractional side of a square, having a tongue at one end to fit into a mortise in the handle; and *c* is an extended curved arm, forming an extension of the handle and cast in the same piece, having about half of its upper surface corrugated. *d* is a pin or pivot passing through both sides of the mortise in the handle and through the tongue on the arm *b*.

Construction and Operation.

The wrench may be constructed of any size, care being taken to proportion the parts so that when put together the distances from the pin *d* to the extremity of the curved arm *c* and to the extremity of the short side of the movable arm *b* may be equal, and may be applied to any nut of a size equal to or smaller than the square forming the inside of the arm *b*. The arm *b* being adjusted so that its short and upper sides are in contact with two sides of the nut to be turned, the handle *a* is moved so as to bring the curved arm *c* in contact with a third side of the nut, which is thus held firmly with a grip increasing in proportion to the force applied to the handle and necessary to turn it.

I claim the above-described wrench as an improved article of manufacture.

A. M. OLDS.
